(57) **CLAIM**

The ornamental design for a combination cap and cord, as shown and described.

DESCRIPTION

FIG. 1 is a front perspective view of a combination cap and cord.

FIG. 2 is a front view thereof.

FIG. 3 is a left-side view thereof.

FIG. 4 is a right-side view thereof.

FIG. 5 is a top view thereof.

FIG. 6 is a back view thereof.

FIG. 7 is a bottom view thereof.

FIG. 8 is a bottom perspective view showing a sweatband element folded down; and,

FIG. 9 is a bottom perspective view showing the cord separated from the cap.

The various styles of surface shading applied to the surface of the combination cap and cord represent a contrast in appearance.

The broken lines illustrating portions of the combination cap and cord form no part of the claimed design.
